(57) **CLAIM**

We claim the ornamental design for a measuring instrument, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first aspect of a measuring instrument showing our new, original, and ornamental design, in a first embodiment;

FIG. 2 is a left side view of the aspect of FIG. 1;

FIG. 3 is a right side view of the aspect of FIG. 1;

FIG. 4 is a rear view of the aspect of FIG. 1;

FIG. 5 is a top view of the aspect of FIG. 1;

FIG. 6 is a bottom view of the aspect of FIG. 1;

FIG. 7 is a front perspective view of the aspect of FIG. 1; FIG. 8 is a front view of the aspect of FIG. 1, in a second configuration;

FIG. 9 is a left side view of the aspect of FIG. 8;

FIG. 10 is a right side view of the aspect of FIG. 8;

FIG. 11 is a rear view of the aspect of FIG. 8;

FIG. 12 is a top view of the aspect of FIG. 8;

FIG. 13 is a bottom view of the aspect of FIG. 8;

FIG. 14 is a front perspective view of the aspect of FIG. 8; FIG. 15 is a front view of the aspect of FIG. 1, in a third configuration;

FIG. 16 is a left side view of the aspect of FIG. 15;

FIG. 17 is a right side view of the aspect of FIG. 15;

FIG. 18 is a rear view of the aspect of FIG. 15;

FIG. 19 is a top view of the aspect of FIG. 15;

FIG. 20 is a bottom view of the aspect of FIG. 15; and,

FIG. 21 is a front perspective view of the aspect of FIG. 15.
